UNITED STATES PATENT OFFICE

WILLIAM J. HELMQUEST, OF SAN FRANCISCO, CALIFORNIA

DESIGN FOR A PHOTOGRAPH MOUNT

Application filed September 24, 1929. Serial No. 32,851. Term of patent 3½ years.

To all whom it may concern:

Be it known that I, WILLIAM J. HELMQUEST, a citizen of the United States, and resident of San Francisco, county of San Francisco, and State of California, have invented a new, original, and ornamental Design for Photograph Mount, of which the following is a specification, reference being had to the accompanying drawing, forming part thereof.

The figure is a perspective view of a photograph mount, showing my new design.

I claim:

The ornamental design for a photograph mount, substantially as shown.

WILLIAM J. HELMQUEST.
